UNITED STATES PATENT OFFICE.

GEORGE W. JOHNSON, OF NEWTON, ILLINOIS.

WATCH-MAKER'S TOOL.

SPECIFICATION forming part of Letters Patent No. 252,222, dated January 10, 1882.

Application filed December 3, 1881. (No model.)

To all whom it may concern:

Be it known that I, GEORGE W. JOHNSON, of Newton, in the county of Jasper and State of Illinois, have invented a new and Improved 5 Watch-Maker's Tool, of which the following is a full, clear, and exact description.

My invention consists of a pincher-shaped tool or implement for removing rollers from the balance wheel posts of watch-movements, one 10 of the jaws of the tool being flattened and divided to form fingers or tines adapted to be passed between the balance-wheel and the roller, straddle of the post, the other jaw being formed with a passage, perforation, or recess for the reception of the pivot of the post, so that the end of the jaw will rest upon the shoulder of the post where power is applied to 15 the handles of the tool for forcing off the roller.

Reference is to be had to the accompanying 20 drawings, forming part of this specification, in which similar letters of reference indicate corresponding parts in both the figures.

Figure 1 is a sectional side elevation of my 25 invention as it appears when applied for removing a roller; and Fig. 2 is a sectional plan view of the same, taken on the line $x-x$, Fig. 1.

The jaw a of the tool or implement A is flattened at the end and divided to form the fingers or tines c , which are adapted to straddle the post d of the balance-wheel f , and to 30

pass between the wheel and the circular plate or roller e , as clearly shown in Fig. 1.

The jaw b of the tool or implement is preferably curved over, as shown, and the end of it is formed with the hole or recess i , which is 35 of suitable size and depth to receive the pivot g of the post, so that the end of the jaw will rest upon the shoulder j of the post, (which is formed by reducing the same to form the pivot,) which furnishes a solid support for the jaw 40 when power is applied to the handles of the tool or implement for forcing the roller off from the post.

By means of this tool the rollers or circular plates may be quickly and easily removed from 45 the post without danger of breaking the roller or bending or otherwise injuring the post or the pivots thereof.

Having thus described my invention, I claim as new and desire to secure by Letters Patent— 50

The tool herein shown and described, consisting of the jaws a and b , the jaw a being flattened and divided to form the fingers or tines c , the jaw b being formed with the recess i , substantially as and for the purposes 55 set forth.

GEORGE WASHINGTON JOHNSON.
